UNITED STATES PATENT OFFICE.

CHARLES HENRY SCHOPBACH, OF AURORA, ILLINOIS, ASSIGNOR TO SIMON FLUSHEIM AND NORMAN S. FLUSHEIM, OF CHICAGO, ILLINOIS, COPARTNERS UNDER NAME OF THE CHICAGO CORSET COMPANY.

ABDOMINAL CORSET.

SPECIFICATION forming part of Letters Patent No. 732,378, dated June 30, 1903.

Application filed January 10, 1901. Serial No. 42,735. (No model.)

To all whom it may concern:

Be it known that I, CHARLES HENRY SCHOPBACH, of Aurora, in the county of Kane and State of Illinois, have invented certain new and useful Improvements in Abdominal Corsets; and I do hereby declare that the following is a full, clear, and exact description thereof, reference being had to the accompanying drawings, and to the letters of reference 10 marked thereon, which form a part of this specification.

This invention relates to improvements in corsets, and refers more particularly to corsets which are provided with abdominal bands 15 or belts and with devices for attaching to a corset certain articles of wearing-apparel which are adapted to be sustained by the corset—as, for instance, hose-supporters or one of the nether garments.

20 The invention consists in the matters hereinafter set forth, and more particularly pointed out in the appended claim.

In the drawings, Figure 1 is a perspective view of the front lower portion of a corset, 25 showing my invention applied thereto. Fig. 2 is a fragmentary view of parts of the corset shown in Fig. 1 with the abdominal band removed. Fig. 3 is a rear view of the central portion of said abdominal band. Fig. 4 30 is a detail section taken on line 4 4 of Fig. 1. Fig. 5 is a sectional detail of the attaching button or stud and associated parts on said line 4 4 of Fig. 1. Fig. 6 is a detail section taken on line 6 6 of Fig. 1. Fig. 7 shows a 35 sectional detail of a modified form of attaching device.

As shown in said drawings, A designates the body of the corset provided at its front meeting edges with the usual stiffening strips 40 or steels A' A', one of which is provided with studs a and the other of which is provided with an equal number of eyelets or loops a', adapted to engage said studs to fasten the corset in a familiar manner.

45 B designates an abdominal band which passes around the forward lower marginal part of the corset in a familiar manner. Said band is detachably secured at its center to the front of the corset and is attached at its

ends to the sides of the corset by means of 50 buckles a², said band being made of considerable width at its middle and tapered at its ends to form straps of suitable width to engage said buckles. One of the features of my invention is embraced in an improved 55 means for detachably connecting the middle of said band with the corset. This part of my invention embraces features as follows:

C designates two buttons or studs which are secured to the front of the corset near the lower 60 edge thereof, on each side of the meeting edges thereof, and which are adapted to engage eyelets b, located in the middle portion of the abdominal band. Said eyelets are herein shown as formed by short rigid tubes b', which pass 65 through and are secured permanently in the body of the fabric and are closed at their outer ends by heads b², between which and washers b³, surrounding the inner ends thereof, the body of the band is clamped. Said 70 buttons or studs C are secured to the body fabric of the corset by shanks C', which pass therethrough, the inner ends of said shanks being engaged by washers C², over which said shank is clenched, as shown in Fig. 5. The 75 heads C³ of said buttons or studs, which are made from sheet metal, are provided with slits c, which render the same expansible and contractible, whereby they may be inserted into the eyelet and held therein by the engagement 80 due to the spring of the metal of which they are made. Loops a³ a³ are attached to the corset-body on each side thereof between said detachable fastening devices and the buckles and through which the intermediate portions 85 of said band pass. Said loops serve to hold the band in proper position with respect to the corset. The lower front edge of the corset will be made of flexible material between the stays or bones thereof, permitting the same 90 to be contracted when the band is tightened, such flexible parts folding upon themselves, as shown at a⁴ in Fig. 1. As the pull on the center of the band will be mainly upward, the eyelets will be placed near the lower edge of 95 the band, thereby keeping the latter from curling or rolling up.

As a further improvement I have provided

means for detachably suspending a hose supporter from the above-mentioned attaching devices by which the band is centrally connected with the corset, or a nether garment 5 may be suspended from the corset.

As shown in Figs. 1 and 5, D D designate the upper ends of elastic hose-supporters of usual form provided with slotted plates D'. E designates a double-flanged washer, which 10 is mounted on the shank C' of the button or stud C and between the flange c' on said shank and the outer face of the body of the corset. Said washer is provided between its flanges with a somewhat deep peripheral 15 groove, within which the slotted plate of the supporter is inserted when it is slipped over the shank C'. The slot of said plate is enlarged, as common in such devices, to permit the same to be passed over the flange c' of 20 said button or stud.

In Fig. 7 is shown a modification of the attaching button or stud, which is adapted for attaching a nether garment, such as an underskirt, to and suspending from the corset. 25 As shown in said figure, the part which corresponds with the stud or button C of the previously-described figures has the form of a disk F, attached to the outer end of a rigid neck F', and which disk is larger in diameter than said first-described button or stud 30 and forms a button of ordinary size. The other parts of the attaching device are like that heretofore described and are designated by the same reference-letters. The grooved 35 washer E is located on the shank C' inside of said button, between the flange c' and the body of the corset, and is adapted for engagement by the plate of the hose-supporter, said supporter being attached thereto before the 40 garment supported thereby is fastened in place. It will be understood that when a nether garment is to be supported from the corset any desired number of buttons of any preferred construction will be employed, 45 which will be spaced at suitable intervals around the corset, and that such set of buttons will include one or more buttons or studs like that shown in Fig. 7, which latter will be located on the corset in suitable positions 50 for engagement with the upper ends of the hose-supporters.

So far as described the fasteners for securing the belt at the center and which hold it distended vertically are not adapted to prevent the belt from disengaging itself from the 55 lower part of the corset when the latter is bent in by a stooping or sitting position, as in those positions the release of outward stress against the corset slackens both corset and belt, so that they tend to work apart. To make the engagement of both parts positive under all conditions, a hook H is secured vertically to the interior face of the central portion of the band. Said hook has its tongue 60 h pointing upward. An eyelet h' is correspondingly secured in the corset to engage said hook. The pull on the band being down-

ward, the hook resists this when placed in the position described, as well as securing the corset and belt against displacement when 70 the outward pressure of the wearer's body is removed because of a stooping or sitting position. Thereby the fasteners C are relieved of all strain which tends to separate their parts. 75

The means described for attaching the central part of the abdominal band to the corset affords an exceedingly strong and reliable connection between the same without undue or unsightly projecting parts or portions 80 which are so prominent as to prevent a suitably-smooth fit or appearance of the outside garments. This is because of the fact that the button or stud, on the one hand, and the eyelet, on the other hand, project through 85 the parts to which they are attached and are firmly clamped thereon. The hook is entirely concealed between the corset and belt. Moreover, the construction and arrangement of 90 said attaching device are such that the pull on said band when it is on the corset and tightened is such as to hold the studs or buttons and the eyelets in their engaged positions, so that so long as said band remains tight said parts cannot possibly become disengaged. 95 When the pressure is relieved from any cause, such as a stooping or sitting position, the hook prevents the studs disengaging themselves. Thereby the two parts are held firmly in position, the position of the fasteners on the lower edge of the band preventing the latter from rolling or curling up. Thus the band at all times is supporting the body by its full width and cannot work loose 100 and slip out of place, so as to cause discomfort to the wearer. Furthermore, said construction of the attaching device enables the band to be easily and readily engaged with and disengaged from said corset when desired. 105 So far as the main feature of my invention is concerned said band instead of being attached at its ends to the rear part of the corset may be extended entirely around the corset and its ends attached together or to the corset by means permitting adjustment 110 of the length of the band. 115

The construction of the stud or button which affords engagement therewith of the hose-supporter is of much practical importance, as it avoids the necessity of providing 120 other fastening devices for this purpose and also insures the proper engagement of said supporters with the corset so long as the garment or band, as the case may be, remains properly attached, it being obvious that the 125 supporter being engaged with the shank of the button or stud inside of the band or garment engaged therewith said supporter cannot become accidentally detached from the shank while the garment is in place. 130

I claim as my invention—

An abdominal corset comprising a corset-body having vertical stiffening-strips extending to its lower front edge, an abdominal band

secured at its ends by adjustable fastenings to the lower part of the corset, said band being arranged to rest over the lower part of the front of the corset and to extend upward from the lower margin thereof, means for detachably connecting the lower margin of the band with the lower margin of the corset, consisting of buttons attached to the corset and having expansible heads and metal eyelets in the lower margin of the band adapted to engage said buttons, and an upwardly-opening hook secured centrally to the inner face of the band between said eyelets, and

an eyelet on the corset-body between the buttons adapted to engage said hook, said connecting devices acting to hold the band from upward displacement and to also hold the band transversely distended. 15

In testimony that I claim the foregoing as my invention I affix my signature, in presence 20 of two witnesses, this 9th day of August, A. D. 1900.

CHARLES HENRY SCHOPBACH.
